Primary Examiner—Melody N. Brown*Attorney, Agent, or Firm*—Shinjyu Global IP Counselors,
LLP[57] **CLAIM**

The ornamental design for a bicycle cleat, as shown and described.

DESCRIPTION

FIG. 1 is a top perspective view of a bicycle cleat with a rear projection in accordance with a first embodiment of my new design;

FIG. 2 is a top plan view of the bicycle cleat illustrated in FIG. 1;

FIG. 3 is a rear end elevational view of the bicycle cleat illustrated in FIGS. 1 and 2;

FIG. 4 is a bottom plan view of the bicycle cleat illustrated in FIGS. 1-3;

FIG. 5 is a front end elevational view of the bicycle cleat illustrated in FIGS. 1-4;

FIG. 6 is a right side elevational view of the bicycle cleat illustrated in FIGS. 1-5;

FIG. 7 is a left side elevational view of the bicycle cleat illustrated in FIGS. 1-6;

FIG. 8 is a top perspective view of a bicycle cleat without a rear projection in accordance with a second embodiment of my new design;

FIG. 9 is a top plan view of the bicycle cleat illustrated in FIG. 8;

FIG. 10 is a rear end elevational view of the bicycle cleat illustrated in FIGS. 8 and 9;

FIG. 11 is a bottom plan view of the bicycle cleat illustrated in FIGS. 8-10;

FIG. 12 is a front end elevational view of the bicycle cleat illustrated in FIGS. 8-11;

FIG. 13 is a right side elevational view of the bicycle cleat illustrated in FIGS. 8-12; and,

FIG. 14 is a left side elevational view of the bicycle cleat illustrated in FIGS. 8-13.
